United States Patent Office

Des. 206,862
Patented Feb. 7, 1967

206,862

SERVICE STATION

Albert Shotmeyer, Wyckoff, N.J.
(% Shotmeyer Brothers Co., Hawthorne, N.J. 07507)

Filed Mar. 16, 1966, Ser. No. 1,492

Term of patent 14 years

(Cl. D13—1)

FIG. 1

FIG. 2

FIG. 3

FIG. 1 is a perspective view of a service station showing my new design;

FIG. 2 is a top plan view; and

FIG. 3 is a sectional view taken along the line 3-3 of FIG. 1.

I claim:

The ornamental design for a service station, as shown and described.
